UNITED STATES PATENT OFFICE.

VALENTINE HEPP, OF CHICAGO, ILLINOIS.

IMPROVEMENT IN SANDPAPERING-MACHINES.

Specification forming part of Letters Patent No. **159,574**, dated February 9, 1875; application filed December 12, 1874.

To all whom it may concern:

Be it known that I, VALENTINE HEPP, of Chicago, in the county of Cook and State of Illinois, have invented a new and Improved Sandpapering-Machine, of which the following is a specification:

My improvement in sandpapering-machines consists of a hollow shaft to the frame which carries the heads around, with a shaft running down through it, and carrying a large spur-wheel, which gears with the pad-carrier, so as to divide the motion between the carrying-frame and the driving-shaft, in such a manner as to obtain the requisite rapid motion of the pad-carriers without having to run either the frame or the driving-shaft at a high speed.

Figure 1 is a longitudinal sectional elevation of my improved machine. Fig. 2 is a plan view with a part of the dust-case broken out. Fig. 3 is a detail of the feed-gear in section. Fig. 4 is a section of one of the pad-carrying heads.

Similar letters of reference indicate corresponding parts.

A is the shaft that carries the frame B, on which the pad-carrying heads C are carried over the work. This shaft is made hollow, and a shaft, D, is arranged in it, with a large spur-wheel, E, on its lower end, gearing with the heads C by their pinions F, to revolve them on their own axis. The frame is revolved in one direction by a belt applied to the pulley G, while the wheel E is revolved in the opposite direction by a belt on the pulley H, so

that the motion is equally divided between the carrying-frame and the driver, in such manner that a high speed is obtained for the pads without running the driver or the carrier as high as would be required if all the motion were obtained from one alone. This makes the machine run with less power than as commonly arranged, and consequently with less wear.

The carriage J, whereon the work is carried, is operated by the spur-wheel K, gearing with the toothed rack L, and connected to the bevel-wheel M, with which the two bevel-drivers N and O gear on opposite sides, so as to move the carriage forward and backward, the drivers being turned by the same driving-belt, which shifts from one to the other of the pulleys P Q to reverse the motion.

I am aware that smoothing and rendering uniform the surface of plates by a series of disks rotating about a common center is already known to the public; but

What I claim is—

1. The combination of the hollow shaft A, carrying-frame B, pad-frames C, driving-shaft D, wheel E, and pinions F, substantially as specified.
2. The combination of spur-wheel K, bevel-wheel M, and drivers N O with the toothed bar L of the carriage, substantially as specified.

VALENTINE HEPP.
